UNITED STATES PATENT OFFICE

LESLIE E. STRIEGEL, OF CLEVELAND, OHIO, ASSIGNOR, BY MESNE ASSIGNMENTS, TO THE ALLEN-SHERMAN-HOFF COMPANY, OF PHILADELPHIA, PENNSYLVANIA, A CORPORATION OF PENNSYLVANIA

ASH GATE

Application filed May 15, 1923. Serial No. 639,118.

This invention relates to hoppers and more particularly to hoppers and their closures adapted for receiving and discharging hot ashes or other loose material. In the usual practice ash hoppers are designed to hold the hot ashes until they can be discharged into suitable transporting devices by an opening and closing member beneath the discharge opening. In order to quench the hot ashes to prevent them from injuring the walls of the hopper and stoker parts, considerable water is sprayed on them. It is desirable, therefore, to remove this water in a satisfactory and efficient manner.

15 An object of my invention is to provide for such hoppers a gate construction having a door or gate which will at all times receive and carry to suitable drains easily and quickly all such water or other liquid without allowing it to escape and fall in undesirable places.

These and other objects will be apparent from the following description and annexed drawings, in which—

25 Fig. 1 is a plan view of a twin gate construction showing one of the doors in plan with parts in section as indicated in line 1—1, Fig. 2.

Fig. 2 is a view on line 2—2, Fig. 1, being partly in section and partly in elevation.

30 Fig. 3 is an enlarged vertical section similar to Fig. 2 with the door in partially open position.

Fig. 4 is a vertical section on line 4—4, Fig. 1.

35 Fig. 5 is a section on line 5—5, Fig. 1, with the door omitted.

Figs. 6 and 7 are sections through the troughs in the door taken on lines 6—6 and 40 7—7, Fig. 1.

Fig. 8 is a plan view of a modified form of door.

Fig. 9 is a section on line 9—9, Fig. 8.

45 Fig. 10 is a section on line 10—10, Fig. 8 with the refractory material and face of the hopper indicated.

In the drawings the lower portion of the hopper or bin is indicated at 1 and consists of the usual metal walls 2 lined with fire brick or other refractory material 3. Sur-

rounding the discharge opening of the hopper is a gate construction comprising a frame 4 and a door or gate 5. The frame is supported from the hopper by any suitable means such as an angle iron 6 to which the frame is bolted.

The sides 7 of the frame are preferably of channel construction, each having a vertical web 8, outer flanges 9 and 10, and inwardly extending flanges 11. Connecting the sides 7 of the frame are end members 7^a and 7^b. The outer flanges 10 of the sides form tracks on which the door is supported for reciprocating movement, the door being carried by arms 12 which project through slots 13 in the web 8 and carry rollers 14. The door is reciprocated to open and closed position by any suitable mechanism, such as a door operating piston and cylinder, the piston rod 14' being secured to a bracket 15, carried by the door.

Along the sides and the front end 17 of the door are suitable channels or troughs 18 and 19 for carrying off the water which comes from the material in the hopper. The trough 19 slopes downwardly and outwardly toward the troughs 18 from its midpoint and troughs 18 slope along the sides of the door to the outlets 20' which deliver the water to a stationary trough 25. The troughs 18 partially underlie the inner flanges 11 of the frame members 7 and the front trough 19 underlies a similarly inwardly extending flange 11^a of the cross member 7^b.

The inner flanges 11 extend to a position closely adjacent the outwardly extending flanges 21 forming the inner edges of the trough opening to prevent ashes or other material from falling directly into the trough. The flange 11^a extends to a position closely adjacent the inner wall of the trough 19, as shown in Fig. 2 for the same purpose. If desired, the flanges 11 and 11^a may be cut back or provided with downwardly extending flanges or lips 20 and 20^a. Cooperating with the downwardly extending flanges 20 and 20^a to prevent the water from being forced completely over the edge of the door are the outer flanges 22 of the troughs which are higher than and extend above the flanges

21 and the inner vertical flanges 23 on the door and above the lower edges of the downwardly extending flanges 20 of the frame, thus directing any water which is forced 5 between the flanges 20 and 21 into the troughs 18. At the rear of the door and secured to or forming part of the frame 7 is a downwardly extending flange 26 which directs the water escaping rearwardly into 10 a fixed trough 25. The trough 25 extends adjacent the rear edge of the door to receive the water from the side troughs 18 and from the curved lip 27 at the rear of the door between the troughs 18. The upper edge 25^a 15 of the trough 25 is under the lip 27 at the rear of the door when the door is in closed position, and projects a substantial distance forwardly of said lip to insure receiving the liquid coming over the edge of the door. 20 The trough 25 may have a suitable discharge pipe (not shown) for receiving the water and conducting it where desired.

The part 11^a of the frame 7 may have, if desired, in addition to the downwardly extending flange 20^a an additional rib or flange 20^b which may extend down sufficiently far to be substantially in line with the upper surface of the flange 22 or even slightly below it. Even in the latter case it will not interfere 30 with the operation of the door because the flange 20^b is located inwardly of the flange 22 of the front trough on the door when the door is in closed position. The flange 20^b will of course cooperate with the flange 22 35 to deflect water into the trough 19 and prevent it from passing bodily over the front of the door.

A suitable nozzle, diagrammatically indicated at 30, may be provided for throwing 40 streams of water under pressure in both directions to positively clean the troughs 18 and 19 when desired. The nozzle is preferably carried by the frame 7.

A nozzle 31 is carried by the flange 26 of 45 the frame to assist in removing the refuse from the stationary trough 25 to prevent its becoming clogged with refuse.

In Figs. 8 to 10 a modified form of gate construction is shown. The frame 40 is suspended from the hopper in the usual manner (not shown) and has inwardly extending flanges 41 and downwardly extending flanges 42, the former affording a seat for the refractory material indicated at 43 and forming 50 the inside of the hopper. The door 44 is provided with the front trough 45 which slopes downwardly from the midpoint of the front of the door and curves into the side troughs 46 which underlie the flanges 41 of 55 the frame.

With this construction the troughs are entirely open at the top and are disposed beneath the flanges 41 of the frame and outwardly from the bottom discharge opening 60 of the hopper. With the open trough con-

struction it is of course easier to clean the troughs and remove the refuse therefrom as by a suitable nozzle similar to that indicated in Figs. 2 and 3 or the troughs may be actually cleaned by mechanical means when the door is in open position. 70

In order to provide a suitable means for preventing the water on the upper face of the door from being forced over the side edges of the door, the outer flange 48 of the trough 46 may be made to extend higher than the face of the door, or downwardly extending flanges 47 may be provided to extend below the outer flanges 48 of the trough, thus deflecting the water into the troughs 46. 75

The troughs 46 preferably slope downwardly toward the rear of the door similar to the troughs 18, as shown in Fig. 7, the sides of the door beneath the bottom of the trough 46 being lightened, if desired, as indicated at 49. 80

As indicated in Fig. 10, the door 44 is suspended to reciprocate on tracks 51 outside the flange 42 of the frame, the suspending arms being indicated at 50 in Fig. 8. This construction permits the sides of the door to be located close to the inside of the frame, thus protecting the troughs and also the tracks on which the door is suspended from the ashes or other loose material in the hopper. 85

It will thus be seen that when the door is in closed position the inner downward extending flanges of the frame are disposed closely adjacent flanges on the door to prevent solid material escaping into the liquid drain troughs or into the stationary trough. Consequently, only the very fine material will be carried into the troughs with the liquid and this can be removed by flushing the troughs with the nozzles shown. 100

While the gate constructions have been shown herein as applied to an inwardly sloping hopper and one having metal walls lined with fire brick, it is to be understood that the gate mechanism is applicable to any of the devices of ash hoppers in use, simply by adapting the frame and gate to the particular design of hopper. 105

While the gate construction shown in Figs. 1-3 is a twin gate construction operated by a common cylinder, it is obvious that my invention is applicable as well to a single gate which may be operated by a cylinder or any other suitable operating means. 115

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims. 120

What I claim is:

1. A gate construction for an ash hopper having a bottom opening comprising a frame 130

surrounding said opening and having an inwardly extending member, a door mounted for movement into open and closed position with respect to said opening, said door having drain troughs along a plurality of its sides formed by inner and outer upstanding walls, said troughs being disposed beneath said inwardly extending member, a flange depending from said inwardly extending member between said inner and outer upstanding flanges and extending below the tops thereof.

5 2. The combination with a hopper provided with a bottom discharge opening, of a frame having inwardly extending flanges along its sides, a door mounted to open and close said opening, said door having drain troughs along its sides formed by inner and outer upstanding walls, said troughs being disposed beneath said inwardly extending flanges, and flanges downwardly extending from the inwardly extending flanges and projecting below the tops of the inner walls of said troughs and between the inner and outer walls of said troughs.

10 25 3. In combination with a hopper having a bottom discharge opening, a trough having spaced upstanding walls, a flange projecting from the hopper between said walls, and means beneath the hopper for causing liquid 30 passing through the hopper to be discharged in said trough.

In testimony whereof, I hereunto affix my signature.

LESLIE E. STRIEGEL.
